UNITED STATES PATENT OFFICE.

GEORGE P. WIGGINTON, OF KALAMAZOO, MICHIGAN, ASSIGNOR TO KALAMAZOO LOOSE LEAF BINDER CO., OF KALAMAZOO, MICHIGAN.

TEMPORARY BINDER.

1,241,801.

Specification of Letters Patent.

Patented Oct. 2, 1917.

Application filed February 10, 1916. Serial No. 77,492.

To all whom it may concern:

Be it known that I, GEORGE P. WIGGINTON, a citizen of the United States, residing at Kalamazoo, county of Kalamazoo, State 5 of Michigan, have invented certain new and useful Improvements in Temporary Binders, of which the following is a specification.

This invention relates to improvements 10 in temporary binders.

The main objects of this invention are:

First, to provide in a temporary binder or loose sheet holder an improved adjusting mechanism.

Second, to provide in a temporary binder or loose sheet holder an improved adjusting mechanism which is capable of very accurate or fine adjustments.

Third, to provide an improved temporary 20 binder or loose sheet holder which is capable of rapid manipulation to permit the removal or insertion of sheets or leaves and one which is very secure when adjusted and is simple and compact, so that it may be 25 readily embodied in binders of small size although well adapted for use in binders of large dimensions.

Further objects, and objects relating to 30 structural details, will definitely appear from the detailed description to follow.

I accomplish the objects of my invention by the devices and means described in the following specification. The invention is clearly defined and pointed out in the 35 claims.

A structure which is a preferred embodiment of my invention is clearly illustrated in the accompanying drawing, forming a part of this specification, in which:

40 Figure I is a detail inside plan view of a structure embodying the features of my invention, with the covers extended, the leaves being shown in upright position.

Fig. II is an inverted detail view of the 45 adjusting mechanism of the embodiment shown in Fig. I.

Fig. III is an enlarged detail inverted view similar to that of Fig. II, with the housing or support for the clutch roller re- 50 moved.

Fig. IV is an enlarged detail section on a line corresponding to the broken line 4-4 of Figs. I and III, showing details of the adjusting mechanism.

Fig. V is a plan view of the blank from 55 which the clutch roller housing or support is formed, the same being made as a sheet metal stamping.

Fig. V^A is a detail view of the key employed in the operation of my improved 60 binder when embodied as shown in Figs. I-V.

Fig. VI is a detail plan view of a modified form of the adjusting mechanism.

Fig. VII is an inverted detail view of 65 the embodiment shown in Fig. VI.

Fig. VIII is a detail view similar to that of Fig. VII, with the clutch roller housing or support in section.

Fig. IX is a plan view of the blank from 70 which the clutch roller housing or support of the embodiment shown in Figs. VI, VII and VIII is formed.

Fig. IX^A is a detail of the key employed in the manipulation of the mechanism 75 shown in Figs. VI to IX, inclusive.

Fig. X is an inverted detail view similar to that of Fig. VIII, showing another modified form or embodiment of my invention.

Fig. XI is an inverted detail view similar to Fig. VIII of still another embodiment 80 of my invention.

Fig. XII is an inverted detail view, similar to Fig. VIII, of another embodiment or modification of my invention, a clutch block 85 being substituted for the clutch roller shown in the foregoing figures.

Fig. XIII is a detail section on a line corresponding to line 13-13 of Fig. XII.

In the drawing similar reference characters refer to similar parts throughout the several views, and the sectional views are taken looking in the direction of the little arrows at the ends of the section lines.

Referring to the drawing, the covers 1 95 and 2 are preferably provided with clamping bars or members 3 pivotally connected thereto as shown in my Patent No. 1,022,452, issued to me April 9, 1912. The binding members 4, preferably in the form of 100 flexible strips extend between the covers, being connected to the cover 1 at 5 and to the cover 2 through my improved adjusting mechanism. The cover 2 is provided with a recess or chamber 2' in which the 105 adjusting mechanism is disposed.

This adjusting mechanism comprises a cross head or adjusting member 6 to which

the binding strips are connected. The adjusting member is slidably mounted upon the bar 7 disposed longitudinally of the cover 2. The adjusting member is held in its adjusted position on the bar by means of a clutch which, in the embodiment shown in Figs. I to V, inclusive, consists of a roller 8 having a segmental toothed portion 9. This clutch roller 8 is supported on the 10 under side of the adjusting member by the housing 10, which is formed as a sheet metal stamping, and extends across the bar 7 between the slide loops 11 and has an attaching portion 12 offset at 13 to provide a 15 supporting shoulder for the bar. The opposite end of the housing member is secured upon the rack-like way 14. This way 14 is disposed at an angle to the bar so that when the roller is moved in one direction it is carried into clutching engagement with the edge of the bar, see Fig. III. The housing member has ear-like portions 15 which are struck upwardly to close the ends of the chamber in which the clutch 20 roller is disposed. The clutch roller is thus supported for rotative and lateral movement, it being positively moved laterally by its rotation owing to the engagement of its toothed segment with the rack.

30 To actuate the roller I preferably provide it with an opening 16 adapted to receive the key 17, the opening being flattened on one side and the key correspondingly flattened so that the roller is rotated by turning the 35 key.

The adjusting member is provided with a slot-like opening 18 above the roller to permit the key being engaged and to permit its lateral movement as the roller travels to and from its engaging position.

With the parts thus arranged the stress on the binding strips tends to engage the clutch more tightly.

By providing the rack and segment arrangement the clutch roller is positively actuated to and from its engaging position.

In the modified form of my invention shown in Figs. VI to IX, inclusive, the clutch roller 19 is smooth on its periphery. 50 Its housing or support 21 is provided with a smooth inclined way disposed oppositely to the bar so that the roller is forced into clutching engagement with the bar. The way portion 20 is, in this embodiment, 55 formed integrally with the housing or support member 21, (see Fig. IX,) the housing member having an offset therein constituting the way. In this embodiment the roller is formed with a central opening 22 adapted 60 to receive a key 23 having a bit or tang adapted to swing within the roller and carry it laterally. The housing or support member is provided with a hole 24 for the lower 65 end of the key stem. The adjusting member

In the modification shown in Fig. X the bar 26 is toothed on its edge with which the roller coacts. This insures a very firm clutching action between the roller and bar, although I do not find it an essential in 70 practice. The adjusting member 6 is slotted at 27 so that a pointed instrument may be introduced to shift it to and from engaging position.

In the modification shown in Fig. XI, the 75 roller 28 is toothed to coact with the toothed bar 26.

In the modification shown in Figs. XII and XIII the clutch member 29 is in the form of a wedge block which is supported to 80 coact with the bar 7 substantially in the same manner as the roller clutch.

To facilitate the adjustment of the clutch member 29 its way is provided with rollers 30.

With the parts thus arranged, the binder 85 may be quickly adjusted and is effectively retained in its adjusted position.

With the several embodiments of my invention illustrated and described I believe 90 that the application or adaptation thereof to various forms of binders will be readily understood by those skilled in the art to which my invention relates.

Having thus described my invention, what 95 I claim as new and desire to secure by Letters Patent, is:

1. In a temporary binder, the combination with the covers, of binding strips extending between the covers, a bar disposed longitudinally of one of the covers, an adjusting member to which said binding strips are connected slidably mounted on said bar, a clutch roller having a segmental toothed portion, and means for supporting said clutch roller 100 for lateral and rotative movement mounted on said adjusting member and comprising a rack disposed at an angle to said bar to coact with the teeth of said roller so that the roller tends to move into clutching engagement with the bar when the adjusting member is moved toward the inner end of the covers, said roller being adapted to receive an adjusting key whereby it may be rotated to and from clutching engagement with said 105 bar, said adjusting member having an opening above said roller to receive such key.

2. In a temporary binder, the combination with the covers, of binding strips extending between the covers, a bar disposed longitudinally of one of the covers, an adjusting member to which said binding strips are connected slidably mounted on said bar, a clutch roller having a segmental toothed portion, and means for supporting said clutch roller 120 for lateral and rotative movement mounted on said adjusting member and comprising a rack disposed at an angle to said bar to coact with the teeth of said roller so that the roller tends to move into clutching engage- 125

ment with the bar when the adjusting member is moved toward the inner end of the cover.

3. In a temporary binder, the combination of a binding member, an adjusting means therefor comprising a bar, an adjusting member to which said binding member is connected, a clutch roller having a segmental toothed portion, and means for supporting said clutch roller for lateral and rotative movement mounted on said adjusting member and comprising a rack disposed at an angle to said bar to coact with the teeth of said roller so that the roller is carried into clutching engagement with the bar when the roller is moved in one direction and disengaged therefrom when moved in the opposite direction, said roller being adapted to receive an adjusting key whereby it may be rotated to and from clutching engagement with said bar, said adjusting member having an opening above said roller to receive such key.

4. In a temporary binder, the combination of a binding member, an adjusting means therefor comprising a bar, an adjusting member to which said binding member is connected, a clutch roller having a segmental toothed portion, and means for supporting said clutch roller for lateral and rotative movement mounted on said adjusting member and comprising a rack disposed at an angle to said bar to coact with the teeth of said roller so that the roller is carried into clutching engagement with the bar when the roller is moved in one direction and disengaged therefrom when moved in the opposite direction.

5. In a temporary binder, the combination of a binding member, an adjusting means therefor comprising a bar, a clutch roller coacting with said bar and having a segmental toothed portion, and means for supporting said clutch roller for lateral and rotative movement comprising a rack disposed at an angle to said bar to coact with the teeth of said roller so that the roller is carried into clutching engagement with the bar when the roller is moved in one direction and disengaged therefrom when moved in the opposite direction.

6. In a temporary binder, the combination with the covers, of binding strips extending between the covers, a bar disposed longitudinally of one of the covers, an adjusting member to which said binding strips are connected slidably mounted on said bar, a clutch roller, and means for supporting said clutch roller for lateral and rotative movement comprising a way on said adjusting member disposed at an angle to said bar so that the roller is carried into clutching engagement with the bar when the roller is moved toward the outer end of the cover, said roller being adapted to receive an ad-

justing key whereby it may be adjusted to and from clutching engagement with said bar, said adjusting member having an opening above said roller to receive such key.

7. In a temporary binder, the combination with the covers, of binding strips extending between the covers, a bar disposed longitudinally of one of the covers, an adjusting member to which said binding strips are connected slidably mounted on said bar, a clutch roller, and means for supporting said clutch roller for lateral and rotative movement comprising a way on said adjusting member disposed at an angle to said bar so that the roller is carried into clutching engagement with the bar when the roller is moved toward the outer end of the cover.

8. In a temporary binder, the combination of a binding member, an adjusting means therefor comprising a bar, an adjusting member to which said binding member is connected, a clutch roller coacting with said bar, and means for supporting said clutch roller for adjustment on said adjusting member relative to said bar comprising a way disposed at an angle to said bar so that said roller is carried into clutching engagement with the bar when the roller is moved in one direction and disengaged therefrom when moved in the opposite direction, said roller being adapted to receive an adjusting key whereby it may be adjusted to and from clutching engagement with said bar.

9. In a temporary binder, the combination with the covers, of binding strips extending between the covers, a bar disposed longitudinally of one of the covers, an adjusting member to which said binding strips are connected slidably mounted on said bar, and a clutch roller mounted on said adjusting member to coact with said bar for securing said adjusting member in its adjusted positions thereon.

10. In a temporary binder, the combination with the covers, of binding strips extending between the covers, a bar disposed longitudinally of one of the covers, an adjusting member to which said binding strips are connected slidably mounted on said bar, a clutch member coacting with said bar, and means for supporting said clutch member for adjustment longitudinally of said bar comprising a way on said adjusting member disposed at an angle to said bar so that the clutch member tends to move into clutching engagement with the bar when the adjusting member is moved toward the inner end of the cover.

11. In a temporary binder, the combination with the covers, of binding strips extending between the covers, a bar disposed longitudinally of one of the covers, an adjusting member to which said binding strips are connected slidably mounted on said bar,

and a friction clutch member mounted on said adjusting member to coact with said bar and so that its bar-engaging movement is toward the outer end of the cover, said clutch member being supported so that the movement of the adjusting member toward the inner end of the cover tends to move the clutch member to clutching position.

12. In a temporary binder, the combination with the covers, of binding strips extending between the covers, a bar disposed longitudinally of one of the covers, an adjusting member to which said binding strips

are connected slidably mounted on said bar, and a friction clutch member mounted on said adjusting member to coact with said bar and so that its engaging movement is toward the outer end of the cover.

In witness whereof, I have hereunto set my hand and seal in the presence of two witnesses.
